UNITED STATES PATENT OFFICE

158,814

RECORD CONTROLLED CALCULATING
MACHINE

Carl W. Sundberg, Detroit, Mich., and George H. Kress, Vestal, N. Y., assignors to International Business Machines Corporation, New York, N. Y., a corporation of New York

Application October 5, 1949, Serial No. 5,311

Term of patent 3½ years

(Cl. D64—11)

To all whom it may concern:

Be it known that we, Carl W. Sundberg and George H. Kress, citizens of the United States of America, residing respectively at Detroit, county of Wayne, State of Michigan, and Vestal, county of Broome, State of New York, have invented a new, original, and ornamental Design for a Record Controlled Calculating Machine, of which the following is a specification, reference being had to the accompanying drawing, forming part thereof.

Fig. 1 is a front perspective view of a record controlled calculating machine, showing our new design.

Fig. 2 is a front elevation of the same.

Fig. 3 is a view of the right end of the machine.

The back and left end of the cabinet are plain.

We claim:

The ornamental design for a record controlled calculating machine, as shown and described.

CARL W. SUNDBERG.
GEORGE H. KRESS.
